UNITED STATES PATENT OFFICE.

HERMAN NORECK, OF CHARLOTTESVILLE, VIRGINIA.

BRACKET FOR INCANDESCENT LAMPS.

SPECIFICATION forming part of Letters Patent No. 585,350, dated June 29, 1897.

Application filed March 5, 1897. Serial No. 625,934. (No model.)

To all whom it may concern:

Be it known that I, HERMAN NORECK, a citizen of the United States, residing at Charlottesville, (University Station,) in the county 5 of Albemarle and State of Virginia, have invented certain new and useful Improvements in Brackets for Incandescent Lamps; and I do hereby declare that the following is a full, clear, and exact description of the same, reference being had to the annexed drawing, making a part of this specification, and to the letters of reference marked thereon.

The present invention has reference to that 15 class of incandescent lamps exposed to the weather, and has for its object to provide a bracket that will protect the socket of the lamp and the wires from rain or moisture.

The invention consists in a bracket constructed substantially as shown in the drawing and hereinafter described and claimed.

In the accompanying drawing, which represents a side elevation of my improved bracket partly in section and showing the lamp connected thereto, A B designate the 25 two sections of the bracket, which may be constructed of metal or other waterproof material. The tubular section A, through which the wires C extend, is provided at its lower end with an exterior screw-threaded neck a to receive the interior screw-threaded neck b of the section B. This section B is in the 30 form of a hood, which is of such shape as to extend over and around the usual socket D of the lamp E and protect it from rain or

moisture. The hood closely fits around the 35 socket, so that no rain or moisture can work in between the hood and socket.

To form a sealed joint between the screw-threaded necks a b and provide means for shedding the rain, so that the rain or moisture will not come in contact with the wires, there is provided an overlapping guard c, thereby protecting the wires against injury by contact with rain or moisture.

Having now fully described my invention, 45 what I claim as new, and desire to secure by Letters Patent, is—

A bracket for incandescent lamps, consisting of the tubular section A through which the wires extend, said section having an exterior screw-threaded neck a and an overlapping guard c surrounding said neck and forming a space between the two, and the section B to form a hood to receive the socket of the lamp, said section having an interior screw-threaded neck which fits in the space between the exterior screw-threaded neck and the guard and engaging with the threads of the former, substantially as and for the purpose set forth.

In testimony that I claim the above I have hereunto subscribed my name in the presence of two witnesses.

HERMAN NORECK.
